Primary Examiner — Karen E. Eldridge Powers*Assistant Examiner* — Jasmine Mlinarcik(74) *Attorney, Agent, or Firm* — Michael J. Feigin, Esq.; Feigin & Fridman(57) **CLAIM**

The ornamental design for a mini-necktie, as shown and described.

DESCRIPTION

FIG. 1 shows a top perspective view of a mini-necktie.

FIG. 2 shows a bottom perspective view thereof.

FIG. 3 shows a top plan view thereof.

FIG. 4 shows a bottom plan view thereof; and,

FIG. 5 shows a side elevation view.

The broken lines shown in the drawings represent environmental structure that forms no part of the claimed design.

1 Claim, 5 Drawing Sheets(56)
